CLAIM

The ornamental design for a container for a liquid soap dispenser as shown and described.

DESCRIPTION

FIG. 1 is a perspective view from the front, bottom, and right side of a container for a liquid soap dispenser;
FIG. 2 is a perspective view from the front, top, right side thereof;

FIG. 3 is a perspective view from the front, bottom, and left side thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left side elevational view thereof;

FIG. 9 is a right side elevational view thereof; and,

FIG. 10 is a perspective view from the front, top, right side with lid attached.

The even broken lines in the drawings are for the purpose of illustrating portions of the container for a liquid soap dispenser that form no part of the claimed design. The uneven broken lines illustrate environmental subject matter that form no part of the claimed design.

1 Claim, 10 Drawing Sheets
